J. MCK. McDONALD

COOLER FOR LIQUIDS

Filed March 31, 1924

Inventor:
James McKerchar McDonald
By *Louis Crowley, Jr.*
Attorney.

UNITED STATES PATENT OFFICE.

JAMES MCKERCHAR McDONALD, OF TE PUKE, NEW ZEALAND.

COOLER FOR LIQUIDS.

Application filed March 31, 1924. Serial No. 703,153.

To all whom it may concern:

Be it known that I, JAMES MCKERCHAR McDONALD, subject of the King of Great Britain, residing at Te Puke, Bay of Plenty, in the Dominion of New Zealand, have invented new and useful Improvements in Coolers for Liquids, of which the following is a specification.

This invention has reference to a new and improved construction of appliance that has been devised specially for use in cooling cream, milk and like liquids, but which is also useful for the cooling of any other liquids.

15 The invention covers a construction of apparatus that is particularly adaptable for the regenerative cooling of liquids that have been heated, as for instance cream or milk that has been pasteurized, and for the cold liquid on its passage to the heater being brought into intimate contact with the liquid coming from such heater so that it is progressively cooled and the liquid passing to the heater is progressively heated. The 20 apparatus may however be used as a self contained cooler by the employment of any approved cooling agency, as for instance expanded ammonia gas.

The construction devised provides for the 30 apparatus being simply and cheaply made and for the parts being readily taken apart for cleansing purposes. It also provides for the liquid to be cooled, and also for that being heated when regenerative cooling is being effected, flowing in thin bodies over the surfaces being reciprocally acted upon, or over the surfaces under the action of the cooling medium employed when the appliance acts as a cooler only.

40 This construction is shown in the accompanying drawings in which:—

Figure 1 is a side elevation,

Figure 2 an end elevation,

45 Figure 3 an inside face view of one half of the appliance.

Figure 4 is a cross sectional elevation of the appliance, and

Figure 5 a plan view.

The construction devised consists in an 50 appliance that is formed by two vertical hollow casings A—A' of metal each enclosing a narrow space between its two side walls and having closed ends and bottom. These two casings are adapted to be fitted 55 together side by side, and for this purpose each one is formed at its ends and bottom

with flat flanges B that engage the similar flanges upon the other frame. The two are then clamped tightly together by means of the clamps C, or other approved fastenings, 60 which are made readily removable and replaceable.

The inner wall D of each casing A and A' is formed with corrugations extending longitudinally across it and is disposed so 65 that it lies slightly within the plane of the flanges B. The corrugations on the one casing are made to correspond with those on the other so that when the two casings are assembled together a continuous narrow 70 corrugated passage E is formed between these walls extending from the top to the bottom of the appliance and across the full surface area of the two casings. The walls D at their upper ends are extended and 75 inclined outwards from one another so that a chamber E' is formed at the top.

An inlet pipe F is led into the bottom of the passage E through the end of one casing and an outlet pipe G leads away from 80 one end of the chamber E'. Liquid may therefore be caused to pass up through this passage E by admitting it through the pipe F and allowing it to overflow through the pipe G. In some cases the passage of the 85 liquid may be reversed.

The space enclosed by each casing is covered in by an inwardly and downwardly inclined plate H which serves to form a hopper J between the casing and the extension 90 of the wall D of that casing. This plate is made with perforations h all along its length so that liquid introduced into the hopper will be evenly distributed to flow down over the inside surface of the corrugated wall D. A supply pipe K is provided to introduce the liquid into the hopper J and a draw off pipe M to allow the liquid 95 to flow away from the casing.

In use, the liquid to be cooled is delivered 100 into the respective hoppers J so that it flows in thin streams down the insides of the walls D. At the same time the cooling medium is caused to pass up through the passage E so that it acts through the walls D 105 upon the liquid flowing down the insides thereof. In regenerative cooling this latter liquid will serve to heat the liquid flowing up through the passage E. If a special cooling medium is used, as for instance ammonia, the top of the chamber E' will be 110 closed, the gas passing in through the inlet

F, expanding in the passage and escaping through the outlet G.

Baffle plates N may be disposed at intervals upon the outsides of the respective walls 5 D and so shaped and arranged as to cause the cooling medium to flow positively over the surfaces of these walls as it rises through the passage.

I claim:—

10 A cooler for liquids, comprising two hollow casings positioned side by side and having longitudinally-corrugated inner walls which are spaced slightly apart so as to jointly form a narrow serpentine passage 15 between them, the end and bottom walls of said casings being provided with abutting

marginal flanges; clamps engaging said abutting flanges to secure the two casings together; a trough extending along the upper end of each casing and inclined laterally and downwardly toward the respective corrugated wall thereof, each trough having perforations adjacent its inner longitudinal edge; a supply pipe for delivering liquid to be cooled to each trough to flow across the same and discharge through the perforations therein onto the inner surface of the adjacent corrugated wall; and means for conveying a cooling medium to the serpentine passage to travel therethrough. 20 25 30

In testimony whereof, I affix my signature.
JAMES McKERCHAR McDONALD.
